CLAIM

The ornamental design for a multi-positional holster accessory attachment device, as shown and described.

DESCRIPTION

FIG. 1 is a top and side perspective view of a multi-positional holster accessory attachment device;
FIG. 2 is a top plan view thereof;
FIG. 3 is a rear view thereof; and,
FIG. 4 is a side elevation view, the opposite side view being a mirror image thereof.

The broken lines depict environmental structure and are included for the purpose of illustration only and form no part of the claimed design.
